UNITED STATES PATENT OFFICE.

JOHN A. COOPER, OF ADAIR, IOWA, ASSIGNOR OF ONE-HALF TO A. C. SAVAGE AND G. W. GOODHART, OF SAME PLACE.

MATCH-SAFE.

SPECIFICATION forming part of Letters Patent No. 655,689, dated August 14, 1900.

Application filed February 2, 1900. Serial No. 3,709. (No model.)

To all whom it may concern:

Be it known that I, JOHN A. COOPER, a citizen of the United States, residing at Adair, in the county of Adair and State of Iowa, have 5 invented certain new and useful Improvements in Match-Safes, of which the following is a specification.

This invention relates to that class of match-safes in which a quantity of matches is contained within a holder and the bottom of the holder is grooved and capable of sliding horizontally, so that when the groove is under the receptacle a single match will drop into it and when the bottom is pulled forwardly the 15 match may be grasped.

The object of this invention is to provide a safe of this class which shall be of simple, durable, and inexpensive construction and in which the sliding bottom is formed complete 20 of a single piece of sheet metal and so arranged as to operate accurately in connection with matches of ordinary sizes and shapes and so constructed as to work equally well when the heads of the matches are lying in 25 either direction within the receptacle.

My invention consists in certain details in the construction, arrangement, and combination of the various parts of the device, and particularly in the formation of the sliding 30 bottom piece, whereby the objects contemplated are attained, as hereinafter more fully set forth, pointed out in my claims, and illustrated in the accompanying drawings, in which—

35 Figure 1 shows the entire match-safe in perspective. Fig. 2 shows a vertical central sectional view of the same.

Referring to the accompanying drawings, I have used the reference-numeral 10 to indicate a strip of sheet metal the upper end of 40 which is flat and provided with an opening 11 to receive a nail or hook whereby the device may be suspended from a wall. The lower end of the part 10 projects forwardly at 45 12 and then straight downwardly at 13.

The reference-numeral 14 indicates the sides and front of the match-safe, which parts are secured by solder or other means to the sides of the part 12, said sides projecting 50 rearwardly to a point in alinement with the part 10.

The reference-numeral 15 indicates a hinged

cover pivotally connected with the sides 14 by means of the pintle 16. The lower edge of the sheet-metal sides 14 are bent straight outwardly to form the tracks 17. In the accompanying drawings I have shown an auxiliary back piece 18, arranged in alinement with the part 10 and connected by solder to the sides 14 and projected a considerable distance below the sides 14. This part may, however, be dispensed with, if desired. The bottom of the match-safe is formed complete of a single piece of sheet metal and comprises a flat solid bottom 19 of substantially the same width as the space between the part 13 and the front of the safe. The ends of this bottom piece 19 are bent upwardly and then inwardly at 20 to overlap the tracks 17. The central portion of the front edge of the bottom is bent downwardly, then forwardly, and curved at 21, thus providing means whereby an operator may press his thumb or finger against the bottom to push it rearwardly. At opposite sides of the part 21 two brackets are 75 formed. These brackets comprise strips 22, formed integral with the bottom to project straight forwardly in parallel planes and having the downwardly-curved portions or pockets 23, then bent straight forwardly at 24 beyond the pockets, then curved rearwardly and backwardly at 25 under the bottom 19, and finally upwardly at the point 26. This part 25 serves as a brace, is connected with the bottom by solder or other suitable means, and 85 it touches the lower surface of the depression or pocket 23.

On each side of the forward edge of the bottom 19, between the extensions thereon and the ends 20, I have curved the metal downwardly at 27, thus providing means whereby the heads of matches in the receptacle will not be engaged by the sharp edge of the bottom. 90

A spring 28 is fixed to the rear of the part 12 and its ends engage the rear surface of the bottom 19. Hence when the bottom is pushed to its rearward limit and the pressure removed therefrom the said spring will force the bottom to its forward limit. 95

Within the interior of the receptacle is a 100 rectangular weight 29 to rest upon the top of the matches and to hold them in substantially-parallel planes within the receptacle.

In practical use it is obvious that the sev-

2

eral parts of the match-safe may be made by dies from sheet metal and put together either by soldering or riveting. The bottom is connected with the device by first bending the rear ends 26 straight, then placing the ends 20 of the bottom piece upon the tracks 17, and moving the bottom rearwardly until the ends 26 are in the rear of the part 13. Then these ends 26 are bent upwardly, whereupon the 10 device is ready for use. Assuming that the receptacle is filled with matches, it is obvious that when an operator by pressing his thumb or finger upon the part 21 moves the bottom rearwardly all of the matches within the interior of the receptacle will rest wholly upon the strips or brackets at the front edge of the bottom piece. It is obvious that because the heads of the matches are of greater diameter than the body portions thereof the said heads 20 may project downwardly as far as need be beyond the said brackets, because there is no bottom portion beneath the heads of the matches, and, furthermore, on account of the size of the depressions or pockets 23 only one 25 match may rest therein. Then when the pressure is removed from the part 21 the spring 28 obviously forces the bottom forwardly, whereupon the match may readily be grasped, because its entire central portion between the 30 brackets is exposed. It is obvious, further, that by bending the bottom downwardly at 27 the bottom will not strike against the heads of the matches in such a way as to cause them to be ignited. Furthermore, it is obvious 35 that by bending the ends of the brackets rearwardly under the bottom and then upwardly in the rear of the bottom the said brackets are firmly braced, because the central portion

of the under part engages the bottom of the depression or pocket 23 and is fixed by solder 40 or the like to the bottom 19.

Having thus described my invention, what I claim, and desire to secure by Letters Patent of the United States therefor, is—

1. An improved match-safe, comprising in 45 combination, a suitable match-receptacle open at its bottom, and having tracks in a horizontal plane at its sides near the bottom, a bottom piece, for the receptacle, made of sheet metal, having its ends bent forwardly 50 and outwardly to overlap said tracks, two integral, forwardly-extending brackets, each having a pocket therein, on the said bottom, and yielding pressure devices for normally holding said bottom to the forward limit of 55 its movement.

2. An improved match-safe, comprising in combination, a match-receptacle, having its back piece inclined forwardly to a position near the vertical center of its side piece, 60 tracks on the lower part, or edges of said side pieces, a bottom piece made complete of a single piece of sheet metal, with its edges turned to overlap said tracks and having at its forward edge two forwardly-projecting 65 parts, with pockets or depressions therein, said forwardly-projecting parts being designed to assume a position under the match-receptacle when the bottom is moved to its rearward limit, and yielding pressure devices 70 for normally holding said bottom to its forward limit.

JOHN A. COOPER.
